Attorney

UNITED STATES PATENT OFFICE.

SAMUEL E. GUINN, OF JOHNSON CITY, TENNESSEE, ASSIGNOR TO S. E. GUINN MANUFACTURING CO., OF CINCINNATI, OHIO, A CORPORATION OF NEW YORK.

DESIGN FOR A COMBINED CIGAR LIGHTER AND PAPER WEIGHT.

Application filed October 30, 1924. Serial No. 11,233. Term of patent 14 years.

To all whom it may concern:

Be it known that I, SAMUEL E. GUINN, a citizen of the United States, residing at Johnson City, in the county of Washington and State of Tennessee, have invented a new, original, and ornamental Design for a Combined Cigar Lighter and Paper Weight, of which the following is a specification, reference being had to the accom-

panying drawings, forming part thereof, and in which:—

The figure is a perspective view of the combined cigar lighter and paper weight.

I claim:—

The ornamental design for a combined cigar lighter and paper weight, as shown.

SAMUEL E. GUINN.
